UNITED STATES PATENT OFFICE.

CHARLES P. FREESTATE, OF CHICAGO, ILLINOIS.

STRETCHER-FRAME.

No. 914,261.

Specification of Letters Patent.

Patented March 2, 1909.

Application filed January 18, 1908. Serial No. 410,575.

To all whom it may concern:

Be it known that I, CHARLES P. FREE-
STATE, a citizen of the United States of Amer-
ica, and a resident of Chicago, county of
Cook, State of Illinois, have invented certain
new and useful Improvements in Stretcher-
Frames, of which the following is a specifica-
tion.

The main objects of this invention are to
10 provide an improved form of stretcher frame
particularly adapted for stretching shade
cloth during the operations of sizing and
painting it; to provide an improved con-
struction whereby the rails of such frames
15 may be constructed entirely of metal, thereby
greatly reducing the fire risk in a shade cloth
manufacturing plant; to provide a structure
of this character which is practically free
from parts which are likely to get out of order;
20 to provide a type of stretcher rail to which the
cloth may be readily clamped and in which
the gripping faces of the clamping members
are so arranged as to be protected from accu-
mulations of sizing and paint, and in which
25 the act of shifting the gripping surfaces into
and out of engagement with each other will
tend to spring the parts slightly so as to chip
off any accumulations of paint and sizing
which may have dried upon the outer sur-
30 faces thereof; to provide improved means for
mounting a series of short clamping bars to
a main bar; and to provide an improved
method of hanging a stretcher frame, having
a channel-shaped sheet metal rail, so as to pre-
35 vent the weight of the parts from spreading
the flanges thereof. These objects are ac-
complished by the device shown in the ac-
companying drawings, in which—

Figure 1 is a partial front elevation of a
40 stretcher frame constructed according to this
invention and showing the cloth in position
thereon. Fig. 2 is a rear elevation of the
same, illustrating the advantages of the
hinged lower rail. Fig. 3 is a transverse sec-
45 tion of the upper rail, showing the method of
clamping the cloth thereon and of retaining
the bars in interlocking engagement with
each other. Fig. 4 is a transverse section of
the main bar of the upper rail, showing the
50 method of connecting the hangers thereto.
Fig. 5 is a transverse section of the upper rail,
showing the clamp in its open position and
showing the method of guiding the clamping
bar on the main bar. Fig. 6 is a sectional de-
55 tail of the clamping bar, showing its gripping
surface faced with friction material, such as

rubber, to prevent slipping of the cloth. Fig.
7 is a detail of the lower end of one of the
toggle braces, illustrating the arrangement of
the stud recesses for adjusting the brace. 60
Fig. 8 is an enlarged detail of the hinge joint
in the lower bar.

In the form shown in the drawings, the
stretcher frame comprises an upper rail 1 pro-
vided with hangers 2 for supporting it in a 65
substantially horizontal position and a sec-
ond rail 3 connected with the upper rail 1 by
means of a plurality of toggle braces 4, the
whole frame being suspended in a substan-
tially vertical plane by means of said hang- 70
ers 2. Each of the rails is provided with
clamping means for attaching thereto the
edges of the sheet which is to be stretched.
The upper rail 1 is preferably continuous
throughout its entire length, while the lower 75
rail is preferably divided into sections of con-
venient length, the ends of adjacent sections
being hinged together on axes transverse to
the plane of the frame. The hinges are indi-
cated at 5 in the drawings. 80

In the form shown, the entire frame is con-
structed of metal. The upper rail 1 con-
sists of a main bar 6, preferably formed of
resilient sheet metal, bent to channel-shaped
transverse section, as illustrated in Figs. 3 85
to 5, inclusive, and having mounted thereon
a series of clamping bars 7 which are of
short length and also preferably of channel-
shaped cross-section. This shape of cross-
section permits the bars to be made of com- 90
paratively light metal without sacrificing
rigidity. The clamping jaws, by means of
which the cloth is secured to the upper rail,
comprise the lower shoulders or flanges 8
and 9 of the bars 6 and 7, respectively. The 95
flange 9 of the bar 7 is preferably bent to an
acute angle with the web of said bar, and the
flange 8 is bent to such angle with its web
that it will lie parallel with the flange 9 when
said jaws are in gripping relation, as in Fig. 100
3. The flange 8 is also bent along a longi-
tudinal line so as to extend upwardly a short
distance along the faces of the bars 7 and
provide an edge 10 about which the cloth 11
is folded, as in Fig. 3. This edge 10 also 105
serves as a convenient guide along which the
cloth may be torn when removing it from
the stretcher frame.

In order to provide convenient means for
retaining the bars in gripping engagement 110
with the cloth, the upper flange 12 of the bar
6 is curved inward, and its edge forms a

yielding shoulder which may be sprung over the top of the bars 7, as in Fig. 3. To this end, the upper flange 13 of each bar 7 is inclined inwardly as illustrated in Figs. 3 and 5, so as to wedge the flange 12 outward when the bar 7 is pushed into position between the flanges of the bar 6. The upper flange of each bar 7 is offset either along a continuous line or at suitable intervals, to provide a shoulder or shoulders 14 over which the edge of the flange 12 may be passed to retain the bar 7 in its gripping position.

In order to permit the bars 7 to freely move into and out of gripping position independently of each other, and thereby admit of local adjustment of the cloth, each bar 7 is separately connected to the main bar 6 by guide rods 15 which pass through apertures in the lower flange 9 of the corresponding bar 7. The guide rods 15 are disposed at right angles to the length of the rail. The bar 7 is supported in its open position by means of lugs 16 which extend downwardly from the flange 13 and rest upon the top of the flange 12, as in Fig. 5.

The lower rail 3 has a transverse section exactly like that of the upper rail, with the exception that it is inverted so as to grip the cloth along the upper edge of the rail, and the lugs 16 are also unnecessary on the clamping bars 7 of the lower rail, as said bars will tend to hang in their open position when not engaged by the flange 12.

The toggle braces 4 are each constructed of two bars, the longer bar 17 being preferably of channel-shaped cross-section, and the shorter bar 18 being of angle section. The pivot 19 at the joint between the bars is located slightly out of line with the pivot 20 on the upper bar and the stud 21 on the lower bar when the toggle is in its expanded position, as shown in Fig. 2. The lower end of the bar 17 is provided with a longitudinal slot 22 and a plurality of branch recesses 23, into either of which the stud 21 may be seated for determining the spacing between the rails 1 and 3. The stud 21 is headed so as to prevent the bar 17 from slipping off from it.

The hangers 2 are provided with shanks 24 which extend downwardly through the upper flange 12 of the bar 6 of the upper rail and are riveted into the lower flange 8. The weight of the apparatus is thus carried in a manner which does not tend to spread apart the flanges of the bar 6.

To permit the bars 7 to be readily released from gripping engagement, each is provided with one or more lugs 25 which serve as handles for pulling the shoulders 14 away from the flange 12.

The operation of the device shown is as follows:—All of the studs 21 are seated in corresponding recesses 23 of their braces 4 so that the bar 3 hangs in a certain fixed relation to

the bar 1, corresponding, of course, to the width of the cloth. The operator then passes along the frame, fastening the upper edge of the cloth into the rail 1 by successively moving into gripping position the bars 7 as he unrolls the cloth from a roll. The upper edge of the cloth is first laid over the edge 10 of the flange 8 of the upper rail, and the bars 7 are dropped from their elevated position and pressed into position between the flanges of the bar 6 so that the flange 12 passes over the shoulders 14. After reaching the end of the frame, the operator fastens the lower edge of the cloth into the lower rail 3 as he passes back along the frame. After both edges of the cloth are attached to the frame, the braces 4 are detached from the lower rail and hung up on hooks 26, conveniently located on the rail 1. Sizing is now applied to the cloth; and, while the cloth is still wet, the toggle braces are dropped from their hooks, and the studs 21 are each seated in the proper recess 23, to give the desired amount of stretching to the cloth when the braces are set up. The braces force apart the rails 1 and 3, and the cloth is thus stretched taut. The hinge joints in the lower rail permit each toggle brace 4 to be separately adjusted and set up as the operator passes along the frame, as will be understood from Fig. 2.

What I claim as my invention and desire to secure by Letters Patent is:

1. In a stretcher frame, a rail formed of two parallel bars having co-acting gripping faces at adjacent longitudinal edges, one of said bars having thereon resilient means adapted to be sprung into engagement with said other bar for retaining said gripping faces in clamping engagement, a second rail, and means adapted to force said rails apart to stretch a sheet of material between them.

2. In a stretcher frame, a rail formed of two parallel bars having co-acting gripping faces at their inner edges, one of said bars being formed of resilient sheet metal and having a shoulder at its outer edge adapted to be sprung into interlocking engagement with the other bar for holding said gripping faces in clamping engagement.

3. A stretcher rail, comprising a main bar formed of resilient metal having a flange disposed along one edge and having a shoulder at its other edge, and a plurality of shorter clamping bars adapted to be separately sprung into position between said flange and shoulder for clamping the edge of a sheet of material against said flange.

4. A stretcher rail, comprising a main bar having a flange disposed along one edge thereof and having a shoulder at its other edge, and a plurality of shorter clamping bars each fitting between said flange and shoulder for clamping the edge of a sheet of material against said flange, said main bar and clamping bars being formed to interlock when in

clamping engagement with each other, and one of said bars being formed of resilient metal and being adapted to yieldingly engage the other for retaining said bars in such 5 interlocking engagement.

5. In a stretcher frame, a rail comprising a pair of bars formed of resilient sheet metal and each being of channel shape with a pair of flanges extending toward the other bar, 10 the flanges of one of said bars extending between those of the other, and the flanges at one edge of said bars being adapted to be sprung into interlocking engagement for clamping a sheet of material between the 15 flanges at the other edge, a second rail, and means adapted to force said rails apart to stretch a sheet of material between them.

6. A stretcher rail, comprising a main bar formed of resilient metal and having transversely disposed flanges along opposite edges of one face, a clamping bar adapted to be sprung into position between said flanges and having at one edge a flange adapted to co-act with the adjacent flange of said main bar for 25 gripping the edge of a sheet of material between them, said flange of said clamping bar being perforated, and a transversely disposed guide rod mounted on said main bar and extending through said flange of said clamping 30 bar for securing said bars together, while permitting them to slide one upon the other, to carry said gripping flanges into and out of engagement with each other.

7. A stretcher rail, comprising a pair of 35 bars formed of resilient sheet metal and each being of channel shape with a pair of flanges extending toward the other bar, the flanges of one of said bars extending between those of the other, the flanges at one edge of said 40 bars being adapted to be sprung into interlocking engagement for clamping a sheet of material between the flanges at the other

edge, and guiding means interposed between said bars, being adapted to secure said bars together when the clamping flanges are separated and to guide said clamping flanges into co-operative engagement when said bars are being sprung into interlocking engagement. 45

8. A stretcher, comprising a pair of parallel rails suspended in horizontal position, one above the other, the upper rail comprising a main bar formed of resilient metal having transversely disposed flanges along its upper and lower edges, a clamping bar adapted to be sprung into position between the flanges of said main bar for clamping the edge of a sheet of material against one of the flanges of said main bar, and supporting means extending loosely downwardly through the upper flange of said main bar and being secured to the lower flange of said main bar, whereby the weight of the frame will be carried by said lower flange. 50 55 60

9. A stretcher frame, comprising a pair of parallel rails spaced apart, one above the other, a plurality of braces connecting said rails and each adapted to force the rails apart for stretching a sheet of material secured between them, one of said rails comprising a continuous main bar and a series of shorter clamping bars for securing the fabric to said main bar, and the other of said rails comprising a series of main bars hinged together and free to bend at their joints about axes 70 75 transverse to the plane of the sheet of material to permit said braces to be expanded separately.

Corrections in Letters Patent No. 914,261.

It is hereby certified that in Letters Patent No. 914,261, granted March 2, 1909, upon the application of Charles P. Freestate, of Chicago, Illinois, for an improvement in "Stretcher-Frames," errors appear in the printed specification requiring correction, as follows: In line 109, page 2, the words "their inner" should be stricken out and the words *adjacent longitudinal* inserted instead; in line 114, same page, the period after the word "engagement." should be stricken out and a comma and the following clause inserted: *, a second rail, and means adapted to force said rails apart to stretch a sheet of material between them*; and that the said Letters Patent should be read with these corrections therein that the same may conform to the record of the case in the Patent Office.

Signed and sealed this 6th day of April, A. D., 1909.
